UNITED STATES PATENT OFFICE

156,389

WALL FIXTURE

Julius Howard Vaughan, Russellville, Ala.

Application June 11, 1948, Serial No. 146,905

Term of patent 3½ years

(Cl. D33—3)

To all whom it may concern:

Be it known that I, Julius H. Vaughan, a citizen of the United States, residing at Russellville, in the county of Franklin and State of Alabama, have invented a new, original, and ornamental Design for a Wall Fixture, of which the following is a specification, reference being had to the accompanying drawings forming a part thereof.

Figure 1 is a perspective view of a wall fixture, showing my new design;

Figure 2 is a side elevational view;

Figure 3 is a rear elevational view;

Figure 4 is a top plan view.

I claim:

The ornamental design for a wall fixture, as shown.

JULIUS H. VAUGHAN.
